UNITED STATES PATENT OFFICE.

JOHN W. KEYES, OF CHICAGO, ILLINOIS.

FIRE-BACK FOR STOVES.

SPECIFICATION forming part of Letters Patent No. 341,851, dated May 11, 1886.

Application filed April 25, 1885. Serial No. 163,474. (No model.)

To all whom it may concern:

Be it known that I, JOHN W. KEYES, a citizen of the United States, residing at Chicago, Illinois, have invented a new and useful Improvement in Fire-Backs for Stoves, of which 5 the following is a specification.

My invention is an adjustable fire-back for stoves.

My invention consists in the arrangement of 10 several pieces placed together so as to be moved one upon another, so as to vary the height or length of the fire-back, and also in providing 15 projections upon certain parts and recesses or openings in other parts to receive those projections and enable the parts to be secured together in position.

In the drawings, Figure 1 is a view of the back side of my fire-back, one end being broken away. Fig. 2 is a longitudinal section, 20 and Fig. 3 is a vertical section.

A is the main front piece, and has the bolts 25 a secured to it by any suitable means—the most convenient method is to place the bolts in position in the mold and pour the molten iron around the bolts, so that by the contraction 30 of the metal the bolts will be held securely in place, and will project out from the back side of A and project through the recesses of the other parts when they are all placed together.

B is an auxiliary front piece of about the 35 same length as A, and is provided with vertical slots l, to receive the bolts a and allow the two parts A and B to be moved vertically so as to vary the total height of the fire-back.

At one or both ends of the parts A and B

are placed the extension-pieces C and D, the latter being upon the back side and provided with a slot, s, extending longitudinally so that it can be moved in or out to vary the total 40 length, and the piece C is provided with a larger opening, r, which is of sufficient size vertically and lengthwise to allow the part C to be extended vertically or lengthwise. Notches or spaces o are formed on the end of 45 D, and teeth or projections n are formed on the end of C, so that when the parts C and D are placed together the teeth n will mesh or project into spaces o, and thus retain the parts in position relative to each other vertically, 50 and allow the depth of the combined parts to be varied as may be desired. It will be seen that the bolt a extends through the vertical slot l in the piece B, and through the large square opening r in the plate C, and through 55 the longitudinal slot s in the piece D. The end of the bolt is threaded and fitted with a nut, which may be turned to clamp the several plates together after they have been adjusted in any position or to any dimensions that may 60 be desired.

I claim—

In a fire-back, the combination of a main plate, A, having one or more bolts, a, the plate B, having the vertical slot l, the plate C, having the wide and long opening r, and the plate D, having the horizontal slot s.

JOHN W. KEYES.
